UNITED STATES PATENT OFFICE.

CHARLES A. L. SAUNDERS, OF ELGIN, ILLINOIS.

SHOE LINER.

Application filed December 9, 1921. Serial No. 521,167.

To all whom it may concern:

Be it known that I, CHARLES A. L. SAUNDERS, a citizen of the United States, residing at Elgin, in the county of Kane and State 5 of Illinois, have invented certain new and useful Improvements in Shoe Liners, of which the following is a description.

In making shoes, it is customary to secure the outer sole to the inner sole or insole, by 10 sewing, nailing or the like, so that a row of stitching or nail points appears on the insole, and over this insole is arranged a false lining, so as to make the bottom of the shoe smooth and prevent physical discomfort to 15 the wearer, or excessive wear on the hosiery, and for other reasons well known in the art. This false lining is generally placed into the shoe by hand, holding it concave so that its cemented surface will not contact with the 20 correspondingly cemented surface of the shoe bottom until the parts are in the desired position for assembly, whereupon the lining is spread out smooth and pressed against the bottom of the shoe so as to prevent wrinkles, 25 if possible. It is obvious that it is extremely difficult to place such liners in the shoe with any degree of rapidity, and it is much more difficult to do so when handling narrow shoes.

One of the objects of my invention is to 30 provide an improved means for holding the liner in position while the shoe is placed with its bottom in juxtaposition to the cemented surface of the liner, whereupon the liner is then pressed against the correspondingly cemented surface of the shoe bottom 35 mechanically by air pressure or the like. Another of the objects of my invention is to provide an improved shoe jack having a 40 movable heel portion, so that the shoe be slipped onto the jack without unduly bending or injuring the upper of the shoe. Many other objects and advantages of the construction herein shown and described will be 45 obvious to those skilled in the art from the disclosures herein given.

To this end my invention consists in the novel construction, arrangement and combination of parts herein shown and described, and more particularly pointed out in 50 the claims.

In the drawings, wherein like reference

characters indicate like or corresponding parts,

Fig. 1 is a front elevation of my improved 55 device;

Fig. 2 is a side elevation thereof;

Fig. 3 is a top plan view of the same;

Fig. 4 is a sectional view taken substantially on the line 4—4 of Fig. 1; 60

Fig. 5 is a sectional view taken substantially on the line 5—5 of Fig. 1;

Fig. 6 is a sectional view taken substantially on the line 6—6 of Fig. 5;

Fig. 7 is a sectional view of the jack with 65 a lining sheet thereon, and the shoe shown in dotted lines;

Fig. 8 is a sectional view taken substantially on the line 8—8 of Fig. 7;

Fig. 9 is a sectional view taken substantially on the line 9—9 of Fig. 7;

Fig. 10 is a detail of the heel-operating means of the jack;

Fig. 11 is a plan view of a liner sheet;

Fig. 12 is a sectional view taken substantially on the line 12—12 of Fig. 13, illustrating a modified form of jack; and 75

Fig. 13 is a top plan view of the jack shown in Fig. 12.

In the drawings, wherein I have illustrated the preferred embodiments of my invention, there is shown a hollow jack 1 with a shank portion 2. It will be noted that the jack is concave on its upper surface in transverse cross-section, as indicated at 3, so that 80 when the liner or lining sheet 4 is arranged thereon with its cemented side uppermost, said cemented side will be out of contact with the correspondingly cemented inner surface of the bottom of the shoe 5. Openings or perforations 6 are provided in the concave upper surface of the jack 1, said openings communicating with the hollow interior of the jack.

Secured to the rear end of the jack is a 85 heel plate 7, said heel plate being movable relative to said jack and hinged thereto at its inner edge, as at 8, so that when the shoe 5 is slipped over the jack, the heel plate 7 may be arranged out of the way to the position 90 shown in full lines in Fig. 7, so that the upper of the shoe will not be unduly injured when slipping said shoe onto the jack. After 95 the shoe has been slipped on the jack, the

heel plate 7 is moved into operative position, as shown in dotted lines in Fig. 7, which movement causes the shoe to slide longitudinally relatively to the jack, so that the toe portion of the jack is moved to the proper distance from the heel of the shoe; or in other words, when the heel plate 7 is moved to the dotted line position shown in Fig. 7, the lining sheet 4 is in proper position for its securement to the inner surface of the bottom of the shoe.

In order to securely hold the lining sheet 4 in position on the jack while the shoe is slipped into position, I have provided suction means produced by a pump 8' or the like, arranged at any suitable point, the intake 9 of said pump leading from the interior of the hollow jack, the conduit means therefor comprising a pipe 10 secured to the shank portion 2 of the jack by threading or in any other suitable or equivalent manner. At the discharge outlet 11 of the pump there is arranged a conduit or pipe 12 communicating with the pipe 10 adjacent the upper end thereof so that, as will be hereinafter described, the upper portion of the pipe 10 between said junction and the jack is both a suction pipe and a discharge pipe, successively. Between the pump and the juncture of the pipes 10 and 12, there are arranged valves 13 and 14, one on each of said pipes, said valves being of the gate type, as shown in Figs. 4, 5 and 6 or of any other desired type, whereby the flow through said pipes may be opened or shut off as desired. On each of the pipes 10 and 12 and intermediate the pump and the aforementioned valves, is mounted a valve 15 and 16, respectively. These valves are of the flapper type as shown, or of any suitable or equivalent structure, whereby atmospheric air may be drawn into said pipes 10 and 12.

The valves 13 and 14 each have a controlling arm or lever 17 secured thereto at one end, the other ends of said levers being pivotally connected to a movable bar 18. The bar 18 is provided with a slot 19 intermediate its ends, and through said slot is inserted the end of one arm of a bell crank lever 20—21 said bell crank lever being secured to a rock shaft 22 pivoted to a suitable supporting frame, which may be of any desired or preferred construction. Arms 23 and 24 are also secured to the rock shaft 22, said arms being adapted to alternately engage and operate the flapper valves 15 and 16, as shown most clearly in Figs. 1 and 2.

The valves 13 and 14 are so arranged that they also operate successively, that is, when one is open the other is closed. To the free end of the bell crank arm 21 is secured a connecting rod 25 operated by a treadle or foot lever 26.

The heel plate 7 has a rod 27 pivotally se-

cured thereto (Fig. 7), one end of said rod being secured to a sleeve 28 encircling the upper portion of the conduit 10 and acting as a vertical guide therefor. A second rod 27' is pivoted to the lower end of said rod 27 and to the sleeve 28, the other end of the rod 27' connected to one arm of a bell crank lever 29—30. The bell crank lever 29—30 is pivoted at some suitable fixed point, as for instance, at the upper end of the conduit 12 (Fig. 1), so as to control the movement of the heel plate 7, and the free end of the arm 30 of the bell crank lever is pivotally secured to one end of a connecting rod 31, the other end of the connecting rod being secured to the treadle 26. A spring 32 is preferably arranged to cooperate with the treadle 26 to return it to its inoperative position after the operation thereof.

The operation of the device is as follows: Assuming that the jack is in the position shown in Fig. 7, the lining sheet 4 cemented on its upper surface, is arranged over the upper surface of the jack, with the heel plate in its inoperative position. At this time the valve 13 is open and the valve 14 closed, and the flapper valve 15 is closed and the valve 16 open. Hence the pump will exert a suction on the lining sheet to hold it firmly in place so that the shoe may be arranged on the jack in proper position for the securement of the liner to the cemented inner surface of the bottom of the shoe. Then the treadle 26 is pressed, first throwing the heel plate 7 into operative position, which moves the shoe longitudinally relative to the lining and the jack, if the shoe is not already in the proper position, and with continued movement of the treadle, in the same direction, the valve 13 closes and the valve 14 opens, and at the same time the valve 15 opens and the valve 16 closes, so that air is drawn in through the open flapper valve 15 and discharged through the openings in the hollow jack, spreading the lining sheet flat and forcibly pressing it against the cemented surface of the inner surface of the bottom of the shoe, whereupon the treadle may be released and the shoe removed off the jack.

It will be noted that when the heel portion is forced upwardly into proper operative position into the heel of the shoe, it forces the toe of the shoe forwardly the proper distance from the heel of the jack. The jacks may be made in pairs, that is, one for the right shoe and one for the left, and of suitable designs and sizes for the particular shoes to be operated upon.

In Figs. 12 and 13 there is shown a modified form of jack, that shown being intended for the securement of heel pads to the insoles. These pads may be of felt, leather, or any desired material, and are applied in a manner similarly to the securement of the liners just described. The jack 33 is hollow

and communicates with a conduit 10', similar to the conduit 10. Openings 34 are provided in the upper surface of the jack so that suction or pressure may act on the heel 5 pad placed on the jack. In this modification, the top surface of the jack is straight or plane, but it may be concaved similar to the concave surface of the jack 1, if so desired.

10 The pad with cement on its top is placed on the jack 33 and held by suction. Then the shoe is slipped into position and air pressure applied to force the pad against the heel portion of the heel bottom.

15 It is obvious that the jack 33 and also the jack 1, may be portable or movable, if desired, and inserted into the shoe, the pad being held on the jack by suction. When inserted, air pressure is applied to force the 20 pad home, and the jack then removed for the next shoe.

Having thus described my invention, it is obvious that various immaterial modifications may be made in the same without departing 25 from the spirit of my invention; hence I do not wish to be understood as limiting myself to the exact form, construction, arrangement and combination of parts herein shown and described, or uses mentioned.

What I claim as new and desire to secure by Letters Patent is:

1. In a device of the kind described and in combination, a jack, suction means for holding a shoe lining thereon, and means 35 for releasing said lining when the sheet is properly positioned on the jack.

2. In a device of the kind described and in combination, a jack, suction means for holding a shoe lining thereon, and means for releasing said suction and forcing said lining against the shoe bottom when a shoe is properly positioned on the jack.

3. In a device of the kind described and in combination, a jack, suction means for holding a shoe lining thereon, means for releasing said suction and admitting air under pressure for forcing said lining against the bottom of the shoe when a shoe is properly positioned on the jack.

4. In a device of the kind described and in combination, a jack, suction means for holding a shoe lining therein, means for releasing said suction and admitting air under pressure to said lining for forcibly pressing said lining against the shoe bottom when a shoe is properly positioned on the jack.

5. In a device of the kind described and in combination, a shoe jack, suction means 60 for holding a lining sheet thereon substantially out of contact with the bottom of a shoe, and means for forcing said lining in place against the shoe bottom when a shoe has been properly positioned on the jack.

6. In a device of the kind described and

in combination, a shoe jack, suction means for holding a lining sheet thereon substantially out of contact with the bottom of the shoe, means for properly positioning a shoe on the jack, and means for forcing said lining in place against the shoe bottom when a shoe has been properly positioned on the jack.

7. In a device of the kind described and in combination, a shoe jack, suction means for holding a lining sheet thereon substantially out of contact with a shoe, means for properly positioning the shoe on the jack, and means acting in unison with said positioning means for forcing said lining against the bottom of the shoe when a shoe has been properly positioned on the jack.

8. In a device of the kind described and in combination, a hollow jack having openings in its face, suction-producing means leading through said jack to said face for holding a shoe lining thereon, and means for releasing said lining when a shoe is properly positioned on the jack.

9. In a device of the kind described and in combination, a hollow jack having openings through its face, a pump having a pipe leading to said jack to produce a suction thereat to hold a shoe lining thereon, an air discharge pipe leading to said jack, and means for releasing said suction and admitting said discharged air to said jack to force said lining in place after a shoe has been properly positioned on the jack.

10. In a device of the kind described and in combination, a hollow jack having openings in its face, a pump having a pipe leading to said jack to produce a suction thereat to hold a shoe lining thereon, an air discharge pipe leading to said jack, means for positioning a shoe on said jack for assembly with said lining, and means operable simultaneously with said positioning means for releasing said suction and admitting said discharged air to said jack to force said lining in place after a shoe has been properly positioned on the jack.

11. In a device of the kind described and in combination, a hollow jack having openings on its face, a pump, conduit means leading from said jack to the pump intake, conduit means leading from said jack to the pump discharge, a valve in each of said conduits to control the flow therethrough, an inlet valve in each of said conduits opening to the atmosphere, and means for operating all of said valves in a predetermined manner, whereby said jack will be subjected to suction and pressure successively.

12. In a device of the kind described and in combination, a hollow jack having openings in its face, a pump, a conduit leading from said jack to the pump intake, a second conduit leading from said jack to the pump discharge, a valve in each of said conduits to

control the flow therethrough, means operably connecting said valves together to operate alternately, an inlet valve in each of said conduits between said pump and first-
5 mentioned valve opening to the atmosphere and interconnected to operate alternately, and a single means for operating all of said valves in unison in a predetermined manner, whereby said jack will be subjected to suc-
10 tion and pressure successively.

13. In a device of the kind described and in combination, a shoe jack comprising a main body portion and a heel portion movable relative thereto, suction means for holding a lining sheet to said body portion, the heel portion of said lining lying free on said heel portion of the jack, means for actuating said heel portion into operative position to properly position the lining and bottom of
15 the shoe for securement to one another, and simultaneously releasing said suction and admitting air under pressure for forcing said lining toward the bottom of said shoe.
20

14. The method of making shoes, comprising holding a cemented shoe lining in fixed
25

position on a jack by suction, positioning a shoe on said jack, and then releasing said suction and pressing said lining in place.

15. The method of making shoes, comprising holding a cemented shoe lining in a fixed position on a jack by suction, positioning a shoe on the jack, and then releasing said suction and admitting air under pressure for pressing said lining against the shoe bottom.
30

16. The method of making shoes, comprising holding a cemented shoe lining in a fixed position on the jack by suction, positioning a shoe on the jack out of contact with said cemented surface, and then releasing said suction and admitting air under pressure
35 against the uncemented side of said lining to press said lining in place against the bottom of the shoe.
40

In testimony whereof, I have hereunto signed my name in the presence of two sub-
45 scribing witnesses.

CHARLES A. L. SAUNDERS.
